Inventor:
Artie C. Carlson,
By Shindahl, Parker & Carlson
Attn:

UNITED STATES PATENT OFFICE.

ARTIE C. CARLSON, OF VALPARAISO, INDIANA.

DESIGN FOR A TOY VEHICLE.

Application filed November 10, 1923. Serial No. 7,740. Term of patent 14 years.

To all whom it may concern:

Be it known that I, ARTIE C. CARLSON, a citizen of the United States, residing at Valparaiso, in the county of Porter and State of Indiana, have invented a new, original, and ornamental Design for Toy Vehicles, of which the following is a specification, reference being had to the accompanying drawings, forming part hereof.

Fig. 2 is a top plan view of the same.

Fig. 3 is a front end view.

I claim:

The ornamental design for a toy vehicle substantially as shown.

ARTIE C. CARLSON.
